ENGINE STARTER

Roland Chilton, Keyport, N. J., assignor, by mesne assignments, to Bendix Aviation Corporation, South Bend, Ind., a corporation of Delaware

Application May 4, 1928, Serial No. 275,188
Renewed January 26, 1938

22 Claims. (Cl. 123—179)

This invention relates to engine starters and more particularly to the inertia type of starter wherein the momentum of a rotating mass is utilized to effect, or to assist in the starting of, an internal combustion engine. Inertia starters of the prior art include an automatic means whereby the starter mechanism is disengaged from the engine as soon as the latter begins to function under its own power and such devices usually effect such disengagement, even though the engine stalls after the first firing strokes.

One object of this invention is to provide a starter having means whereby such disengagement may be delayed until the engine has run long enough to avoid danger of stalling.

Another object of the invention is to provide an inertia type of starter wherein the engine may be so engaged that the starter flywheel may act as an auxiliary engine flywheel to carry the engine over the mis-fires that are apt to occur at slow speeds and to smooth out the running of the engine when idling and to permit a reduction in the safe idling speed.

A further object of the invention is to provide an inertia type of starter which may be energized from the engine while the engine is still running and so be in readiness for a re-start should the engine stall or should it be desired to shut the engine off for a short period.

This invention is intended to be particularly useful in connection with engines, such as used on aircraft, which are characterized by the omission of the usual flywheel and, which therefore, depend on the relatively slight flywheel effect of the engine parts and propeller. As a result the minimum safe idling speed of such engines is undesirably high and the slow speed running is apt to be erratic, and stalling of the engine is apt to occur without warning as the result of relatively few misfires.

In manoeuvering hydro-airplanes on the water, for example, as for tying up to a dock, it is found that the minimum safe idling speed produces an undesirably high manoeuvering speed wherefore it is the common practice for the pilot to switch off his engine when he judges that his distance is appropriate for a gentle contact. This often results in a failure to make proper contact with the dock whereby planes are often damaged or commence to drift. Accordingly, one of the main objects of this invention is to so lower and smooth out the idling of the engine that manoeuvres of this kind can be carried out with certainty and without apprehension that the engine may stall at a critical moment.

It will be appreciated that the momentum effect of the starter flywheel, referred to the crank-shaft of the engine, increases with the square of the gear ratio, which ratio is relatively high in inertia starters. Thus in a typical case a five pound flywheel on the starter is equivalent to a five thousand pound flywheel of one foot radius attached to the crankshaft. With such a flywheel, the idling of the engine will be very greatly improved and by the provisions of this invention the starter flywheel is utilized in this way.

Taking as an illustration the case of a twelve cylinder engine, an inertia starter will normally be capable of producing about ten turns of the crankshaft or in other words, the engine would have to mis-fire sixty consecutive times before it stalls when the starter flywheel is maintained in driving connection with the engine according to the provisions of this invention.

Stalling of an engine occurs (without mis-firing) whenever the speed falls low enough for the kinetic energy of the moving parts to be insufficient to carry the engine over a compression stroke.

This minimum speed in the case of aircraft engines, which have relatively slight flywheel effects, is relatively high, and the augmentation of the flywheel effects of the engine parts, by the utilization of the starter flywheel as an engine flywheel while idling, will be expressed by a multiplication of thousands.

When an engine is idling there is an interchange of energy between the engine and its flywheel member which take turns in driving each other during each cycle. Conventional inertia starters are provided with slipping clutches to limit the shock of engagement to the predetermined torque at which the clutch slips; yet in this invention, where the starter remains in engagement with the idling engine, a reversal of torque of the magnitude to which the starter clutches are preferably set might engender undue pounding on the gears. For this reason in the preferred showing there is incorporated an overrunning clutch of relatively low torque capacity, whereby the overrun torque is only a fraction of the maximum torque developed when the starter drives the engine. In this way, a moderate acceleration is applied to the starter, and the engine is permitted to speed up and over-run the starter. In the absence of this provision, the engine would be relatively slow in getting up to speed, because of the restraining influence of the very great inertia effects of the flywheel due to the larger gear ratio. With

- the relatively low limit placed on the torque supplied from the engine to the starter by this special clutch arrangement the engine is free immediately upon starting to assume the speed best suited for warming up, during which the energy taken from the flywheel in starting will be replaced, whereafter the engine may be throttled down to the low idling speed permitted by the availability of the starter flywheel to overcome fluctuations in the engine speed.
- Owing to the large gear ratio employed in the starter, the flywheel would be over-speeded if left permanently in connection with the engine beyond idling speeds, and accordingly there is included in this invention automatic means whereby the starter is disconnected from the engine whenever the flywheel reaches the maximum desired speed, the connection being automatically re-established whenever the flywheel speed falls down to a pre-set minimum.
- The control is such that (provided the starter is not overspeded) the connection of the entire device to the engine may be established or broken at the will of the pilot, so that, when the engine is in normal operation, and until a possible need for a re-start is anticipated, the entire device will be out of action while the connection may be established at any time the pilot wishes to idle his engine or anticipates that it may stall.
- It is pointed out that in a well designed starter mechanism the flywheel will run for many minutes after it has been energized so that the device of this invention may be used for an indefinite number of re-starts after idle periods of several minutes without resource to outside energization, provided the pilot disconnects his control before stopping the engine. Should he accidentally switch off the engine without disconnecting the starter, this condition will be at once called to his attention by the refusal of the engine to cease turning for several seconds warning him to disconnect the starter if he contemplates utilizing its then existing energy for a start in the next few minutes.
- The initial start after prolonged stops will be made in the usual way by energizing the starter from an external power means such as a hand crank or electric motor.
- Various other objects and advantages of the invention will be in part obvious from an inspection of the accompanying drawing and a careful consideration of the following particular description and claims of one form of mechanism embodying my invention.
- In the drawing:
- Figure 1 is a longitudinal section of an inertia type of engine starter in which my present invention is embodied.
- Figure 2 is a fragmentary cross section taken on the line 2-2 of Figure 1 as looking in the direction indicated by the arrows.
- Figure 3 is a fragmentary sectional view taken on the line 3-3 as looking in the direction indicated by the arrows, and discloses the governor weights that control the flywheel speed.
- Figure 4 is a detail view of the hand cranking gears engaged with the main starter gear of Figure 1.
- With reference to Figure 1, 10 designates the crankcase of an engine to be started to which the starter casing 11 is secured as by bolts 12, the concentric relation with the engine drive shaft 13 being assured by a pilot 14.
- A mechanism common to the inertia type of 75 starter comprises a flywheel 15 rigidly mounted upon a shaft 16 having pinion teeth formed thereon for engagement with corresponding teeth of a first reduction gear 17. This first reduction gear drives the second reduction pinion 18 through a preset slipping clutch 19 and the pinion engages the main starter gear 20 which is rigidly secured to the internally splined driving hub 21. The elements above set forth and described have been used in the past in conjunction with a one-way jaw clutch (not shown) which was engaged with a suitable mating clutch on the engine shaft 13 at the will of the operator when the flywheel 15 has been brought up to speed by a power means external to the engine. Such a power means usually consists of a manually operated hand crank drivably connected to the gear 20; or a high speed electric motor directly connected to the flywheel 15. Detailed information as to the construction of the foregoing may be found in my Patent Nos. 1,561,506, 20 1,632,539, 1,637,806, and 1,660,953. In the present invention, the preferred construction as shown in the drawing comprises in addition to the parts enumerated above, a self-contained unit 30 having an engine clutch drum 31 and a starter clutch drum 32 engaged respectively with splines on the engine drive shaft 13 and within the main gear hub 21 of the starter. Thus the engine drum 31 at all times rotates with the engine, and the starter drum 32 at all times rotates with 30 the splined hub 21 of the main starter gear. Rigidly secured coaxially within the drum 31 is the clutch sleeve 33 and rigidly secured in the shank of the starter drum 32 is the pilot tube 34 which rotatably engages the pilot bushing 35 within the sleeve 33. This pilot bearing serves to maintain the drums 31 and 32 in true concentric alignment in spite of possible misalignment between the engine shaft 13 and the spline hub 21, to allow for which a small amount of play is preferably provided in the fit with the splines on the shaft 13 and in the hub 21. The relative end location of the two drums is provided for by the central bolt 36 engaged in the disk 37 of the hub 21, and having a nut 38 engaging a shoulder in the bushing 35. When the starter is removed from the engine the entire clutch unit 30 is withdrawn from the splines on the shaft 13 and may then be removed from the starter by unscrewing the nut 38.
- The drum 32 is provided with an external driving lug 39 engaging one end of a coil 40 normally contracted upon the drum 32. An internal coil 41 is normally expanded within the drum 32 and has an out-turned end 42 engaged within a slot in the driving lug 39. The coil 40 is arranged for expansion of its right hand end into contact with the engine drum 31 and the coil 41 is arranged for contraction of its right hand end into contact with an internal drum 45 by means of the coned extensions 46 and 47 of a control plate 48 which is movable axially by the thrust washer 49 by means of the yoke-lever 50. The internal drum 45 and the clutch drum 32 contain splines with which are respectively engaged alternated friction clutch plates 51 and 52 held in preset frictional engagement by the dish-washer springs 53 adjustable by the nut 54 screw-threaded on the sleeve 33. The internal drum 45 is thus drivably connected to the sleeve 33 and thence 70 to the engine shaft 13 by means of a slipable clutch.
- The coils 40 and 41 comprise one-way driving clutches, the hand of helix being such that the coil 40 will lock with the engine drum 31 (when 75

expanded by the coned extensions 46, 47 of the control plate 48 to drive the engine from the starter, but will permit the engine to over-run the starter when the former starts to run under its own power. Similarly the helix of the coil 41 is such that it will grip the drum 45 to permit the engine to drive the starter through the slipping clutch 51 and 52, whenever the control plate 48 is moved to contract the end of the coil into contact 10 with the drum 45.

The control yoke 50 is carried by a control shaft 55 having a lever 56 to which is connected with a rod 57, which in turn engages the lever 58 and the control handle 59 so that whenever the control 15 handle is pulled to the right the control plate 48 is moved to the left expanding the end of the coil 40 into contact with the drum 31 and contracting the end of the coil 41 into contact with the drum 45, the parts being held in this position by the spring 20 latch 60 engaging a cam 61 on the lever 58. This engagement may be broken at any time by pressing on the control handle 59 which restores the parts to the disengaged position shown.

To prevent over-speeding of the starter mechanism by the engine a centrifugal governor is incorporated, preferably in the flywheel 15. This governor comprises weights 62 radially slideable in grooves in the flywheel hub plate 63. A pressure plate 64 having a conical rim 65 engages the bevel 25 ends of the governor weights 62 under the axial pressures of the spring 66 which surrounds the clutch hub extension 67 and is adjustable by a nut 68. Surrounding this spring, is a sleeve 69 30 integral with the pressure plate 64 and having the thrust button 70 engageable with the lever 58.

The flywheel of the starter may be energized independently of the engine as by a conventional hand crank (not shown) engaged with the bevel cranking gear 71 (Fig. 4) which drives the main 40 starter gear 20 through the bevel pinion 72 and the cranking gear 73.

The operation of the device is as follows:

Assuming that the parts are in their normal position as shown, with both the coils 40 and 41 45 out of contact with the engine drums 31 and internal drum 45 whereby the starter driving mechanism is disengaged from the engine, the starter flywheel 15 may be energized to high speed as by the hand cranking gears just described. The control handle 59 is now pulled to the right 50 expanding the right hand end of the driving coil 40 into contact with the engine drum 31 and so engaging the engine for turning by the starter mechanism. The shock of this engagement is taken by the slipping of the preset main starter clutch 19 in the usual way in inertia starters. When the engine starts it is free to over-run the 55 starter drum 32 by virtue of the well-known one-way action of coil clutches such as shown at 40 but the hand of the inner coil clutch 41 is such that this locks with the inner drum 45 which is therefore driven at engine speed as long as the initial contact of the end of the coil 41 is maintained by the conical projection 47 of the control 60 plate 48. This causes the clutch 51 and 52 to slip and exert a continuous driving effort which accelerates the starter flywheel.

When a predetermined speed is reached the 70 governor weights 62 will move outwardly under the influence of centrifugal force against the action of the spring 66 and, through the cone thrust plate 65, will move the thrust button 70 into contact with the lever 58 which will be operated in clockwise direction relieving the pressure 75 of the coned extension 47 of the control plate 48

from the end of the coil 41 which will release the drum 45 and the engine will cease to drive the starter until such time as the starter speed has decreased to the point at which re-engagement of the coil 41 occurs under the influence of the latch 5 spring 60 acting in opposition to the governor, the latch during the automatic action being in the engaged side of the cam 61, i. e. the opposite side to that shown in Fig. 1. This action will continue as long as the control 59 is left in the pulled out 10 position but the starter can be completely disconnected by pushing on this lever and transferring the cam 61 to the position shown with respect to the latch 60, when the engine is running normally and no immediate need for a re-start or 15 for slow speed idling is anticipated. When the operator anticipates this need, he will pull the control 59 engaging the starter with the engine and automatically re-energizing as described.

As a safety precaution a fixed brake ring 75 is 20 secured to the flywheel housing, so as to be contacted by the governor pressure plate 64 whenever this is moved an abnormal distance to the right. The governor plate is restrained to unitary rotation with the flywheel by the extension flywheel bolts 76 and accordingly will exert a powerful brake effect upon the flywheel causing slippage of the clutch 51 and 52 and preventing further increase in flywheel speed, even though for any reason, such as a possible disarrangement of the control connections, the coil 41 has failed to disengage the drum 45. It will be seen that when the control means is in the operating position, the one-way action of the coil clutches gives a driving connection from the flywheel to the engine through the high torque starter clutch 19 whenever the engine tends to fall below starter speed, and through the low torque clutch 51 and 52 whenever the engine is over-running the starter until the governor control disengages the coil 41. 40 Thus the starter will be automatically energized from the running engine whenever the control is maintained in the operative position and will automatically drive the engine whenever it tends to fall below starter speed. In other words, due to 45 the high gear reduction employed, the very great momentum of the high speed starter flywheel is available as a powerful idling flywheel for the engine, while a restart may be made within several minutes following the switching off of the engine 50 without re-energizing the starter.

Variations may be resorted to within the scope of the invention and portions of the improvements may be used without the others, whilst not departing from the spirit of the invention.

Having thus described my invention, I claim:

1. In an engine starter, the combination with an engine having a drive shaft, of a flywheel, a gear train, a load limiting clutch in said gear train, a member driven from the flywheel 60 through said gear train, means in connection with said member adapted to engage and drive the engine shaft when its relative speed as determined by the gear train ratio falls below that of the flywheel, a second load limiting clutch of 65 lesser capacity than the first said clutch, a member driven from the drive shaft and provided with means to engage the gear train and to drive the flywheel through said gear train and said load limiting clutches when the relative speed of 70 the flywheel falls below that of the drive shaft, and means manually operable adapted to make said engaging means effective or ineffective.

2. In an engine starter, the combination with an engine having a drive shaft, of a flywheel, a 75

gear train, engaging means driven from the flywheel through said gear train and adapted to drivably engage the engine shaft, engaging means driven from the engine shaft and adapted 5 to drivably engage the gear train for the energization of the flywheel, automatic means controlled by the speed of the flywheel and adapted to cause either of said engaging means to become effective or ineffective, and means manually operable to 10 control the functioning of said automatic means.

3. In an engine starter, the combination with an engine having a drive shaft, of a flywheel, a gear train, a load limiting clutch in said gear train, a normally free engaging means connectable with said gear train and engine shaft and comprising a load limiting clutch of lesser torque capacity than the first said clutch; said engaging means adapted to drivably engage the engine shaft for driving from the flywheel when the relative speed of the shaft falls below that of the flywheel as determined by the gear ratio and to drive the flywheel from the engine shaft when the relative speed of the flywheel falls below that of the shaft, automatic governor means actuated 15 by the speed of the flywheel and adapted to bring into effect said engaging means in the manner stated, and means manually operable to control the functioning of said automatic means.

4. In an engine starter of the character employing an inertia member as a means for supplying starting energy to the engine, the combination with said inertia member of an engine member, and means for maintaining driving engagement between said engine member and said inertia member, said last named means including a movable coupling, the movement of which is controlled by said inertia member, and means responsive solely to the speed of said inertia member for controlling the movement of said coupling.

5. In a starter, the combination with an engine, of a high speed driving shaft, means including a gear train and a one-way clutch for drivably connecting said shaft to said engine to start the latter, and means spaced from said clutch and tending constantly to hold said one-way clutch in position to resume the cranking in the event the engine speed falls after accelerating sufficiently to overrun said clutch.

6. In a starter, the combination with an engine of a high speed driving shaft, means including a gear train and a one-way clutch for drivably connecting said shaft to said engine to start the latter, said clutch including means tending constantly to hold said one-way clutch in position to resume the cranking in the event the engine speed falls after having previously accelerated sufficiently to overrun said clutch, and means including a second one-way clutch operating to 55 transmit the drive in the reverse direction for the purpose of re-energizing said high speed shaft sufficiently to make such resumption of cranking possible.

7. In a starter, the combination with an engine of a high speed driving shaft, means including a gear train and a one-way clutch for drivably connecting said shaft to said engine to start the latter, and resilient means tending constantly to hold said one-way clutch in position 60 to resume the cranking in the event the engine speed falls after having previously accelerated sufficiently to overrun said clutch, means including a second one-way clutch operating to transmit the drive in the reverse direction for the purpose of re-energizing said high speed shaft suffi-

ciently to make such resumption of cranking possible, and means for rendering both said one-way clutch devices inoperative, said means being responsive to acceleration of said driving shaft to a predetermined maximum speed.

8. The method of controlling interchange of power between a flywheel and engine crankshaft which includes the steps of interposing a gear train therebetween in such manner as to cause its high speed end to be rotatable with the flywheel and its low speed end rotatable with said crankshaft, disconnecting the gear train from the crankshaft during initial acceleration of the flywheel, then connecting the gear train with the crankshaft to secure initial rotation of the crankshaft and subsequent receleration of the flywheel.

9. The method of controlling interchange of power between a flywheel and engine crankshaft which includes the steps of interposing a gear train therebetween in such manner as to cause its high speed end to be rotatable with the flywheel and its low speed end rotatable with said crankshaft, disconnecting the gear train from the crankshaft during initial acceleration of the flywheel, then connecting the gear train with the crankshaft to secure initial rotation of the crankshaft and subsequent receleration of the flywheel, and then releasing the connection between the crankshaft and flywheel when the speed of the latter rises to a predetermined magnitude.

10. The method of controlling interchange of power between a flywheel and engine crankshaft which includes the steps of interposing multiple part clutch means therebetween in such manner as to cause its high speed end to be rotatable with the flywheel and its low speed end rotatable with said crankshaft, disconnecting one part of said clutch means from the crankshaft during initial acceleration of the flywheel, then connecting another part of said clutch means with the crankshaft to secure initial rotation of the crankshaft and subsequent receleration of the flywheel.

11. The method of controlling interchange of power between a flywheel and engine crankshaft which includes the steps of interposing multiple part clutch means therebetween in such manner as to cause its high speed end to be rotatable with the flywheel and its low speed end rotatable with said crankshaft, disconnecting one part of said clutch means from the crankshaft during initial acceleration of the flywheel, then connecting another part of said clutch means with the crankshaft to secure initial rotation of the crankshaft and subsequent receleration of the flywheel, and then releasing the connection between the crankshaft and the flywheel when the speed of the latter rises to a predetermined magnitude.

12. In a starter of the class described, the combination with an engine to be started of a shaft rotatable to high speed, a gear train connected to said shaft, means including linkage operated from said shaft to drivably connect the engine and gear train whenever the engine speed tends to fall below the relative speed of the high speed shaft as determined by the gear train ratio, and resilient means engaging said linkage and adapted to automatically maintain said engagement for the driving of the high speed shaft from the engine whenever the high speed shaft speed drops below a predetermined degree.

13. In combination with an engine crankshaft and an enclosing crank-case, a starter housing mounted on said crank-case, an inertia member disposed within said starter housing, means oper-

able from said inertia member to impart initial rotary movement to said crankshaft and means for causing said crankshaft to be re-started after a stop, said re-starting means including connections for temporarily transferring energy from said crankshaft directly to said inertia member and subsequently returning the temporarily transferred energy to the crankshaft.

14. In an engine starter, the combination with an engine, of a high speed shaft, means including a gear train having low and high speed stages operated from the engine when started to drive the high speed shaft, and means adapted to sever the drive at the low speed stage whenever the high speed shaft is accelerated to a predetermined speed, said severing means comprising an element rotatable at the speed of said shaft.

15. In a starter, the combination with an engine, of a high speed shaft, a gear train having low and high speed stages for drivably connecting the high speed shaft to the engine for rotation of the high speed shaft, means for disconnecting the low speed stage from the high speed stage and means rotatable at the speed of said high speed shaft to operate said disconnecting means when a predetermined fixed speed of the high speed shaft is reached.

16. In a starter for an internal combustion engine, in combination with the engine, a rotatable inertia member, an overrunning clutch interposed between said inertia member and engine, means including a gear train operable by the engine and through the instrumentality of said overrunning clutch for storing energy in the inertia member, and means engageable with said gear train to provide the initial storage of energy in said inertia member for subsequent use in providing initial rotation of the engine.

17. In an engine starter, the combination with an engine member and a driving member, of means including a one-way clutch for transmitting a one-to-one ratio drive from said driving member to said engine member, and means including a second one-way clutch for transmitting torque from said engine member to said driving member also at the ratio of one-to-one.

18. In a starter, the combination with an engine, of a high speed driving shaft, means including a gear train and a one-way clutch for drivably connecting said shaft to said engine to start the latter, and compressible means co-oper-

ating with said clutch and tending constantly to hold said one-way clutch in position to resume the cranking in the event the engine speed falls after accelerating sufficiently to overrun said clutch.

19. The method of controlling interchange of power between a starting member and engine crankshaft which includes the steps of interposing a gear train therebetween in such manner as to cause its high speed end to be rotatable with the starting member and its low speed end rotatable with said crankshaft, disconnecting the gear train from the crankshaft during initial acceleration of the starting member, then connecting the gear train with the crankshaft to secure initial rotation of the crankshaft and subsequent reacceleration of the starting member.

20. In an engine starter, the combination with a rotatable element and a flexible member, of a unitary device comprising one portion operative with said flexible member and another portion operating with said rotatable element, means whereby said portions will be coupled together under normal conditions of load and whereby said portions will become operatively disengaged under abnormal conditions of load, and means for coupling said first-named portion of said unitary device to said flexible member for operation in unison therewith.

21. In an engine starter, the combination with a rotatable element and a coiled spring, of a unitary device comprising one portion operative with said coiled spring and another portion operating with said rotatable element, means whereby said portions will be coupled together under normal conditions of load and whereby said portions will become operatively disengaged under abnormal conditions of load, and means for coupling said first-named portion of said unitary device to said flexible member, for operation in unison therewith.

22. In a starter, the combination with an engine, of a driving shaft, means including a clutch for drivably connecting said shaft to said engine to start the latter, and means including a spring cooperating with said clutch and tending constantly to hold said clutch in position to resume the cranking in the event the engine speed falls after accelerating sufficiently to overrun said clutch.

ROLAND CHILTON.
